UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

THREAD-UNWINDER.

1,216,289.

Specification of Letters Patent. Patented Feb. 20, 1917.

Application filed May 5, 1916. Serial No. 95,555.

To all whom it may concern:

Be it known that I, ALBERT H. DE VOE, a citizen of the United States, residing at Westfield, in the county of Union and State 5 of New Jersey, have invented certain new and useful Improvements in Thread-Unwinders, of which the following is a specification, reference being had therein to the accompanying drawings.

10 This invention has for its object to facilitate the unwinding of the thread from a spool or cop without liability of "spilling" or detachment of loose coils from the mass of thread.

15 Heretofore it has been common to apply to the end of a thread-spool a shield in the form of a disk having a smooth periphery overhanging the mass of thread to provide a lead of the thread outwardly to avoid 20 restraint by engagement with adjacent coils. This expedient has been found effective while the edge of the disk remained smooth and bright to permit the thread to slide across and around the same in being drawn 25 from the supply; but any roughness in the edge of the disk due to rust or other cause reduced the effectiveness of the device.

It has also been proposed to mount upon the spool or its support a rotary guide having 30 an eye for passage of the thread or an arm adapted to engage the thread in its passage from the spool. In such case, a sudden pull upon the thread was liable to produce a whirl of the rotary guide at 35 greater speed than the normal unwinding operation, thereby causing the objectionable "spilling" referred to.

According to the present improvement the desirable features of both of these expedients have been incorporated in an unwinder 40 comprising an exceedingly light, rotary shield-member having a spindle journaled for rotation axially of the mass of thread and a smooth rim overhanging the mass, the shield-member being normally stationary. As the thread is taken through a guide in substantially axial relation to the thread-spool or cop, it is drawn across and circularly around the periphery of the shield-member without sufficient friction thereon to cause its rotation; but in case of any abnormal resistance to the unwinding by reason of the overlapping of the coils of thread or other means, the shield-member is caused

by the friction of the thread thereon to rotate with the unwinding of the thread, its continued rotation under momentum having no further effect upon the thread after the strain upon the latter has been relieved.

The invention will be understood by reference to the accompanying drawings, in which Figure 1 is a perspective view representing a spool of thread provided with an unwinder embodying the present improvement and resting upon a spool stand of a common form; and Fig. 2 is an elevation of the same partly in section and with the thread-guide omitted.

As represented in the drawing, the mass of thread 1 is wound in coils upon a wooden 70 spool 2 of usual form having the central aperture 3 entered by the pin 4 extending upwardly from the base 5 of a spool-stand of well-known form. The base 5 has at one end the apertured boss 6 in which is 75 secured the lower end of the rod 7 having reduced upper end portion 8 terminating in the thread-eye 9 through which the thread 1 is led from the spool to a sewing machine.

Entering the aperture 3 of the spool is 80 a plug 10 having at the upper end a flange 11 resting upon the top of the spool and provided with an axial bearing socket 13. To insure strength, stiffness and lightness, the rotary shield-member is preferably formed 85 of a blank of hard wire having the body portion formed into a ring 14 with one extremity 14' abutted against and preferably soldered to the angle with the other extremity of an upwardly and inwardly extending arm 15 which terminates in a downwardly extending spindle 16 entering the bearing socket 13 and having a conical extremity 17 resting upon the bottom of the socket 13.

The outer rim of the member 14 is continuous and perfectly smooth so that the coil being drawn from the spool is permitted to slide freely around it as it is drawn upwardly through the guide-eye 9; but in case 100 the thread should be drawn taut by reason of the adherence of the coil being unwound with another coil, or by an abnormal pull upon the thread from some other cause, the friction of the thread upon the ring 14 will 105 be rendered ineffective as a resistance to unwinding by reason of the rotation of the ring thereby induced. As soon as the thread

becomes slackened, it will merely rest against the rim of the ring 14 while the latter continues to rotate under its momentum, but its unwinding will not be hastened 5 thereby because of the relief of the frictional contact and the omission of any shoulders upon the rotating member which could catch the thread and carry it around the spool.

The plug 10 with its flange 11 constitutes 10 a holder or support to afford an axial bearing for the shield-member 14 which is disposed preferably at the level of the upper flange of the spool 2 so as to insure the lead of the thread in all cases without objection- 15 able contact with said flange.

Having thus set forth the nature of the invention, what I claim herein is:—

A spool-unwinder comprising a rotary shield-member constructed of a wire blank having its body portion formed into a ring 20 with continuous outer rim and extending inwardly to the center of curvature of said ring and then axially downward to afford a stem, and a holder or support provided with a bearing socket to receive said stem 25 and to sustain the same axially of the component coils of a mass of thread.

In testimony whereof, I have signed my name to this specification.

ALBERT H. DE VOE.
